NONWIND SAFETY DEVICE FOR CLOTHES WRINGERS

Harvey W. Williams, Richmond, Calif.

Application March 23, 1948, Serial No. 16,608

2 Claims. (Cl. 68—249)

1

This invention relates to improvements in wringers, and is specifically designed to prevent anything from wrapping about the wringer rollers, such as the wash, or even the hair of an operator which might be caught in the wringer rollers, and is not dependent upon the conventional roller release but which operates automatically whether the rollers are electrically driven or driven by some other source of power, such as an internal combustion engine, and therefore is an improvement over my abandoned copending application Serial Number 774,269, filed September 16, 1947, which operates with equal efficiency but is dependent upon breaking of the electrical circuit for stopping the rollers.

As is well known, it is quite common for articles of apparel and household linens, particularly fringed napkins, or other articles which have loose strands, to wrap around the roller, and, when the hair of the laundress is accidentally caught in the rollers, the person will almost invariably try to pull the hair loose with the hair continuing to wind and finally tearing the hair from the scalp or possibly actually scalping the person, because under such conditions the conventional safety release is almost invariably forgotten.

With washed articles, the winding is never noticed because it occurs on the opposite side of the wringer and if the winding increases too much it may break the wringer, and often the safety release is forgotten until too late to prevent damage, or injury.

This invention provides a means which is actuated as soon as any material starts winding about the rollers to instantly stop and free the rollers, so that the material can be withdrawn. This is particularly important where the hair of the operator is concerned because the pulling which is invariably resorted to will definitely draw the hair out from the free rollers. The rollers having been de-clutched cannot advance in the same direction. To start the rollers again it is necessary to again operate the clutch lever on the wringer.

The objects and advantages of the invention are as follows:

First, to provide a non-wind safety device for wringers which will instantly free the rollers as soon as anything starts to wind about the roller.

Second, to provide a device as outlined which will free the rollers irrespective of whether the material starts winding about the upper or the lower roller.

5 Third, to provide a device as outlined which will remain inoperative until the wringer is manually reset for operation.

Fourth, to provide a device as outlined which will free the rollers irrespective of the direction of rotation of the rollers.

10 Fifth, to provide a device as outlined which is positive in action, simple in construction, and which can be incorporated as an integral part of a wringer assembly, or made as an attachment for installation on existing wringers.

In describing the invention reference will be had to the accompanying drawings, in which:

Fig. 1 is a side elevation of a wringer with the central roller portion broken out and partly shown in section, and showing the invention applied thereto.

Fig. 2 is a reduced scale section taken on line 2—2 of Fig. 1.

Fig. 3 is a reduced scale section taken on line 25 3—3 of Fig. 1.

Fig. 4 is a reduced scale top plan view of one end of the wringer with the head removed to show the releasing mechanism and is taken on a line 4—4 of Fig. 1.

30 Fig. 5 is a top plan view of a modification of the releasing mechanism.

Fig. 6 is a section taken on line 6—6 of Fig. 5.

Fig. 7 is another modification showing rollers substituted for the arcuate shoes for actuating the releasing mechanism.

35 Fig. 8 is a section taken on line 8—8 of Fig. 1.

The invention includes a shoe for each roller, respectively 10 and 11 each of which is concavely formed to fit closely the rollers 12, 13, having just a running clearance 14 so that any 40 object adhering to the roller will engage the edge of the shoe, or wedge between the shoe and the roller.

The shoe 10 for the lower roller has an arm 45 at each end, respectively 15 and 16, which are journaled on the roller shaft 17 and the arm 15 has an upward extension 18 terminating in an engaging member 19, while the arm 16 at the other end has also an upward extension 20 terminating in an actuating member 21.

The shoe 11 for the upper roller also has an arm at each end, respectively 22 and 23, journaled on the respective ends of the roller shaft 24, and the arm 22 has a dependent portion 25 terminating in a cooperative engaging member 26 to engage the member 19 to actuate the lower shoe through engagement of winding material with the upper shoe.

A pair of fingers, respectively 27 and 28, are independently mounted on the two portions 29 and 30 of a telescopic shaft which in turn is pivotally supported at its opposite ends in the housing 31. Adjustable shoes 32 and 33 are mounted in the ends of these respective fingers and cooperate with the respective ends of the actuating member 21. Two lever arms 34 and 35 are respectively secured at one end to the respective portions 29 and 30 of the telescopic shaft and respectively actuate the fingers 27 and 28, and the other ends of these arms have pivotal connection to a pair of plungers 36 and 37 as indicated at 38 and 39, and these plungers slidably operate in the upper part of the gear housing 40 and terminate in cooperative relation to a pin 41 which projects from the de-clutching and reversing lever shaft 42 on which the de-clutching and reversing lever 43 is mounted.

The operation of the invention is as follows:

With the rollers 12 and 13 cooperatively rotating in opposite directions with the roller 12 rotating in the direction indicated by the arrow 44, the clothes will pass directly through the wringer as indicated at 45. If anything starts to wind about the lower roller as indicated at 46, it will engage or wedge between the roller and the shoe 10 carrying the shoe with the roller in the direction of the arrow 44. This swings the engaging member 19 in the direction of the arrow 45, and coincidentally moves the actuating member 21 in the same direction. The side 21' of this member raises the shoe 32 and thus swings the finger 27 upwardly and the lever arm 34 backwardly, forcing the plunger 36 back to throw the lever 43 to neutral position through the medium of the pin 41. The rollers are now de-clutched and entirely free. The material which is wound can now be pulled free with substantially no resistance, or the rollers can easily be turned by hand to free the material. This feature is very important when the hair of the laundress gets caught in the wringer since human hair invariably clings to and winds about the wringer rollers, and with the slight clearance, a very small amount of the hair will wedge between the shoe and roller and stop the rollers.

To start the wringer it is necessary to move the lever 43 to its clutching position which, through the pin 41 forces the plunger back, depressing the end 21' of the actuating member and resetting the shoe.

If the material winds about the upper roller, it engages the upper shoe 11 which moves in the direction indicated by the arrow 47, which through the cooperative engaging member 26 moves the lower shoe in the direction 44 and thus actuating the release in the same manner and direction.

The modification shown in Figs. 5 and 6 is intended for older styles of wringers as an attachment to be mounted on top and front of the gear housing, and includes the shoe 10' slightly clearing the roller as indicated at 14', and with the shoe integral with an arm 16', and consists of a housing 48 in which is slidably mounted two plungers 49 and 50 which are tapered at

one end as indicated at 51 and 52 and having engaging slots 53 and 54 at the start of the tapers. These plungers each have a collar 55 fixed thereon and urged against a stop 56 by a compression spring 57 with the other end of the plunger projecting rearwardly through the housing as indicated at 58.

A different actuating member 59 is formed on the upwardly extending arm of the lower roller 10 and spans the space between the leaf springs 60 and 61 which are anchored at 62 and 63 and slidably retained at 64 and 65 and which engage in the slots 53 and 54.

To operate the wringer, the lever 43 is moved 15 from its neutral position to clutching position on either side according to the direction of rotation desired for the rollers. This forces the plunger in from the position shown for the plunger 49 to that shown for plunger 50 20 against the urging of the spring 57, and the spring 60 engages in the slot 53 and locks the plunger in that position. If the safety is not required, the plungers will always remain depressed as indicated for the plunger 50, so that 25 after the wringer has been once reversed, the plungers will both be depressed and locked, and will never be brought into use unless something winds on one of the rollers. In that case, the shoe 10' or 11 will be moved with the roller, moving the member 59 in the direction occupied by 30 the lever 43, moving the spring 60 or 61 back to release the plunger which through the spring 57 drives the lever 43 to neutral position, freeing the rollers. The plunger is automatically set 35 the next time the lever 43 is moved to that side for clutching.

Instead of the flat shoes, small rollers 66 and 67 can be substituted for the concave shoes 10 and 11, being rotatably supported in the arms 40 15' and 22' as illustrated in Fig. 7.

It will be noted that with either type of device, irrespective of whether the material winds about the upper or the lower roller, the rollers will be instantly freed and will remain free until the gear shift lever is again manually moved to proper position, and that this movement will automatically set the safety device after it has been tripped.

I claim:

1. A non-wind safety device for a wringer having a reverse lever and upper and lower rollers, comprising; a shoe for each roller and slightly clearing the non-cooperative peripheries of the respective rollers and each having an arm at each end journaled on the shaft for its roller and with the arms at one end operatively coupled for opposite movements of the respective shoes about the rollers; and two plungers cooperatively related at one end to said reverse lever and at the other end to one of said arms and each movable to one position through movement of said reverse lever to respective forward and reverse engaging positions for the rollers, and movable respectively to another position through movement of either of said shoes in either direction to move said reverse lever to a non-engaging position for the rollers.

2. In a non-wind safety device for a wringer having a pair of rollers and a reversing and disengaging lever; a shoe extending throughout the length of one roller and slightly clearing the periphery of the roller on the non-cooperative side and having an arm at each end journaled on the shaft for the roller, two plungers having each 70 one end cooperatively related to said reversing

and disengaging lever and the other end operatively related to said shoe for selective operation through opposite movements of the shoe, and movable selectively to operative position for the shoe through movement of said reversing and disengaging lever to the respective forward and reverse positions, and movable by the shoe to disengaging position for said reversing and disengaging lever when material starts winding about the roller; and in which a second shoe is provided for the other roller and with the shoes operatively connected for moving said reversing

and disengaging lever with movement of either shoe in either direction.

HARVEY W. WILLIAMS.
